Patented Sept. 7, 1926.

UNITED STATES PATENT OFFICE.

WILLIAM W. CARGILL AND JOHN GRAVES, OF MADISON, WISCONSIN, ASSIGNEES TO
FRENCH BATTERY COMPANY, OF MADISON, WISCONSIN, A CORPORATION OF WIS-
CONSIN.

FLASH LIGHT.

Application filed April 26, 1924. Serial No. 709,136.

This invention relates particularly to flash-lights of the type employing a tubular casing and a dry cell or a plurality of dry cells confined within the casing, affording 5 a battery.

The primary object is to provide a simple, cheap, and very effective construction which will serve to properly confine the dry cells and obviate danger of injury to 10 the lamp bulb. A still further object is to provide a construction having provision for preventing the cells from causing injury to the lamp, said construction being of non-short-circuiting character.

15 The invention is illustrated in its preferred embodiment in the accompanying drawing, in which—

Figure 1 represents a longitudinal sectional view of the improved flash-light embodying our invention; Fig. 2, a fragmentary sectional view at the upper portion of the casing; and Fig. 3, a broken longitudinal sectional view illustrating a modification.

25 Referring to Figs. 1 and 2, A represents a tubular casing which preferably is composed of insulating material; B, a reflector mounted in one end of the casing and carrying a lamp bulb B'; C, dry cells contained 30 in the casing; D, a spacing and anchoring ring confined in the casing above the uppermost cell; and E, a switch controlling the electric circuit.

The casing A may be composed of hard 35 fibre or other suitable material. It is equipped at its front end with a threaded ferrule 1 upon which is removably mounted a threaded retainer-ring 2 which serves to secure the lens 3 in position. The lens 3 40 serves, in turn, to secure the reflector in position.

The spacing-ring D preferably is of insulating material. It may comprise a heavy paste board ring.

45 In electrical contact with the reflector B is a conductor-strip 4 which may consist of a strip of brass, for example. The outer terminal of the lamp is in electrical contact with the reflector B and through said reflector with the strip 4. One end of the strip 4 makes contact with the central contact 5 of the uppermost cell.

50 A second conductor-strip 6 extends within the ring D and makes contact with the central contact of the lamp bulb.

A third conductor-strip 7 is in electrical connection with the zinc cup of the lowermost cell. The switch E is provided with a movable member 8 which is adapted to complete the circuit by forming a connection between the members 6 and 7.

The strip 4 is an L-shaped strip having one portion 4^a extending along the inner surface of the upper portion of the tube and having another portion 4^b extending snugly through the perforation 9 in the spacing-ring D. The strip is of a somewhat stiff, resilient nature so that the portion 4^b affords a suitable contact member for engaging the terminal 5 of the upper cell. The portion 4^a is secured to the shell A by means of a rivet 10, whose outer end is housed in a countersink 11, so that the rivet does not make contact with the ferrule 1. The ferrule 1 terminates flush with the upper end of the shell A, and the reflector flange is narrow enough to prevent any danger of contact between it and the retainer-ring 2. Thus, the metal which composes the ferrule 1 and the retainer-ring 2 is not "alive," or energized.

55 The strip 6 is of angular form. It has an arm 6^a which extends along the inner wall of the casing and has an arm 6^b which extends snugly through a slot or perforation 12 in the spacing-ring 9. The arm 6^b serves as a contact which engages the central contact of the lamp bulb. In the illustration given, an insulation disk 13 is shown cemented to the underside of the end portion of the arm 6^b. Ordinarily, this piece of insulation is not required because of the air gap between the terminals 4^b and 6^b. The insulation disk may be used to prevent possibility of the members 4^b and 6^b being forced together.

60 The lower end of the strip 6^a is turned outwardly and passed through a slot or perforation a in the wall of the casing, and the extremity of the strip is bent upwardly 100 to form a contact as indicated at 6^c. In the illustration given, the strip is shown secured to the casing wall by means of a rivet 14, which may be omitted if desired. In practice, spacing-ring D is forced into 105 the tube under sufficient pressure to insure a tight fit, and the ring is anchored in its proper position by the strips 4 and 6, which are secured to the casing.

At its rear end, the casing is fitted with 110

a threaded ferrule 15, upon which is screwed a removable cap 16. A conical spring 17 is interposed between the bottom of the zinc cup of the lower cell and the end wall of the cup 16. The lower end of the strip 7 preferably is extended out of the lower end of the tube A and then bent upwardly and interposed between the ferrule 15 and the wall of the casing, as indicated at 7^a.
 10 The strip 7 thus is in electrical connection with the cap 16. If desired, the strip 7 may be secured to the casing wall by a rivet 18 which may serve also to secure the ferrule 15 in position. At its upper end 15 the strip 7 is connected by a rivet 19 with the housing 20 of the switch E. Thus, it will be understood that by moving the sliding contact member 8 of the switch, the gap between the conductor-strip 6 and the conductor-strip 7 may be closed.

In the modification shown in Fig. 3, A' represents the casing. The construction is similar to the construction previously described, except that the reflector and attendant parts are made larger. In this case, a conductor-strip 4^c is employed which corresponds with the conductor-strip 4 previously described. Here, the strip 4^c is so positioned that its upper end will serve as a spring contact which engages the reflector B^c near the base portion of the reflector.

The spacing-ring D serves as a bumper block interposed between the lamp and the uppermost cell, the lower edge of the ring affording a shoulder against which the upper end of the cell butts. The strips 4 and 6 serve to anchor the ring, and, in turn, the spring arms 4^b and 6^b are supported on the ring. By this construction, the contact arms 4^b and 6^b are of sufficient length to gain a desired resiliency and to insure contact between said arms and the central contact of the lamp bulb on the one hand and the central contact of the upper cell on the other hand.

The foregoing detailed description has been given for clearness of understanding, and no unnecessary limitations should be understood therefrom.

50 What we regard as new, and desire to secure by Letters Patent, is:

1. A flash-light comprising a casing, a reflector mounted in one end of the casing, a lamp-bulb mounted in said reflector, a battery between the lamp-bulb and the opposite end of the casing, a hollow spacing-ring above the battery, a conductor-strip in electrical contact with said reflector and having a contact portion extending within the space encircled by said ring and engaging the central contact of the battery, a second conductor-strip extending through the space within said ring and having a contact portion engaging the central terminal of said lamp-bulb, a third conductor strip in elec-

trical connection with a zinc cup of the battery, and a switch adapted to make electrical connection between said second-mentioned and third-mentioned conductor-strips.

2. A flash-light comprising a casing, a reflector mounted in one end of said casing, a lamp-bulb mounted in said reflector, a conductor-strip contacting with said reflector and having at its lower portion an in-turned arm, a second conductor having at its upper portion an in-turned arm, a hollow cylindrical spacing-ring within said casing having perforations through which said in-turned arms extend, a battery located below said spacing-ring and having a central contact engaging said first-mentioned in-turned arm, the central contact of the lamp-bulb engaging said second-mentioned in-turned arm, a third conductor-strip in electrical connection with the lower portion of the battery and having its upper end spaced with relation to the lower end of said second-mentioned conductor-strip, and a switch mounted on the side of the casing and adapted to close the connection between said second-mentioned conductor-strip and said third-mentioned conductor-strip.

3. A flash-light comprising a casing of insulating material, a ferrule mounted on one end of said casing, a lens retaining-ring mounted on said ferrule, a reflector insulatingly mounted in the casing with respect to said ferrule and lens retaining-ring, a lens surmounting said reflector, a lamp-bulb mounted in said reflector, a conductor-strip in electrical contact with said reflector and insulatingly mounted with respect to said ferrule and said lens retaining-ring, a spacing-ring within said casing having a perforation through which said conductor-strip extends, a battery within said casing whose uppermost cell engages said ring and whose central contact engages said strip, a second conductor-strip having an arm engaging the central contact of the lamp-bulb and extending through a perforation in said spacing ring and having a downturned arm extending to a switch, a third conductor-strip in electrical contact with the lowermost cup of the battery and having its upper end spaced with relation to the lower end of said second-mentioned conductor-strip, and a switch mounted on the side of the casing and adapted to close the gap between said second-mentioned conductor-strip and said third-mentioned conductor-strip.

4. A flash-light comprising a casing of insulating material, a cap on one end of said casing, dry cells in said casing, a spring interposed between the lower cell and said cap, a conductor-strip electrically connected with said cap and extending upwardly along the inner side of the casing, a spacing-ring having its lower edge engaging the upper-

most cell, a reflector insulatingly mounted in said casing above said spacing-ring, a conductor strip riveted to said casing and in electrical contact with said reflector, said conductor-strip having an inturned arm extending through a perforation in said ring and engaging the central contact of the uppermost cell, a lamp-bulb mounted in said reflector, a conductor-strip having an in-turned arm extending through a perforation

15

in said ring and engaging the central contact of the lamp-bulb, said last-mentioned strip having a depending portion extending along the inner side of the casing and having its lower end secured to the casing, and a switch interposed between said first-mentioned and last-mentioned contact strips.

WILLIAM W. CARGILL.
JOHN GRAVES.
